UNITED STATES PATENT OFFICE.

CLIFFORD A. JOYNER, OF MUNCIE, INDIANA.

BOAT-PROPELLING DEVICE.

Application filed June 26, 1923. Serial No. 647,934.

To all whom it may concern:

Be it known that I, CLIFFORD A. JOYNER, a citizen of the United States, residing at Muncie, in the county of Delaware, State of Indiana, have invented a new and useful Boat-Propelling Device; and I do hereby declare the following to be a full, clear, and exact description of the invention, such as will enable others skilled in the art to which it appertains to make and use the same.

The invention relates to boat propelling devices, and has for its object to provide a device of this character which is manually operated and which rotates a propeller through a gear train, upon the oscillation of a pivoted handle having a pitman connection with one of the gears in the gear train.

A further object is to provide one of the gears of the gear train with a weight acting as a fly wheel for adding momentum during the operation of the device and insuring a positive operation thereof.

A further object is to mount the device on a single bracket thereby allowing the device to be applied to various types of boats, for instance a row boat, launch or canoe.

A further object is to provide the rear end of the bracket with spaced bearings, in which bearings the propeller drive shaft is mounted, and between which spaced bearings the propeller drive shaft gear is disposed and driven through a gear train connection with an operating lever, and a pit-

man. With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit of the invention.

In the drawing:—

Figure 1 is a side elevation of a conventional form of boat, showing the propelling means applied thereto.

Figure 2 is a top plan view of the propelling device.

Referring to the drawing, the numeral 1 designates a conventional form of boat, which is preferably a small one and 2 a seat disposed therein. Secured to the inner side of the bottom 3 of the boat by means of rivets 4 is an elongated bracket 5, which

bracket is preferably formed from superimposed bars 6, the rear ends of which are provided with spaced upwardly extending arms 7 in bearings 8 of which the propeller shaft 9 is rotatably mounted. Extending upwardly and rearwardly from the forward end of the upper bar 6 is an integral arm 10, to the end of which is pivotally connected at 11 an operating lever 12. When the device is operated, the operator preferably seats himself on the seat 2, then grasps the cross handle 13 of the operating lever 12, and oscillates the same on its pivotal point 11. Connected to the lower end 14 of the operating lever 12 by means of a universal connection 15 is a pitman 16. The pitman extends rearwardly and is pivotally connected at 17 to the main drive gear 18. Drive gear 18 meshes with a small gear 19, which is carried by a large horizontally disposed gear 20, which gear 20 meshes with the propeller shaft carried gear 21, consequently it will be seen that when the main drive gear 18 is rapidly rotated by the oscillation of the operating lever 12, the propeller shaft 9 will be rapidly rotated and consequently the propeller 22 will be rapidly rotated for propelling the boat. To add momentum to the operation of the motor, a fly wheel 23 is provided on the upper side of the gear 20, which fly wheel insures a steady operation of the gear train and adds momentum to the moving parts of the motor during the operation thereof.

From the above it will be seen that a hand operated motor is provided for small craft which is positive in its operation, carried by a single bracket and may be easily and quickly attached to a boat and operated by a single person or a number of persons. It will also be seen that by providing a gear train that rapid rotation of the propeller 22 may be obtained upon a single oscillation of the handle member 12.

The invention having been set forth what is claimed as new and useful is:—

A manually operated motor for small craft, said motor comprising an elongated bracket adapted to be secured to a boat, spaced arms carried by the rear end of said bracket, a propeller drive shaft mounted in bearings of said spaced arms, a gear carried by the propeller drive shaft and disposed between the spaced arms, a gear train carried by said bracket and geared to the gear carried by the propeller drive shaft between

the spaced arms, the forward end of said bracket being provided with upwardly and rearwardly extending arm, an operating lever pivotally connected to said arm and a pitman connection between the operating lever and a gear of the gear train.

In testimony whereof I have signed my

name to this specification in the presence of two subscribing witnesses.

CLIFFORD A. JOYNER.
